(57) **CLAIM**

The ornamental design for a modular flooring tile with cable channels, as shown and described.

DESCRIPTION

FIG. 1 is a top isometric partially exploded view of a modular flooring tile with cable channels showing our new design, with fasteners at the top left and bottom right corners in a first position and fasteners at the top right and bottom left corners in a second position.

FIG. 2 is a top plan view of the modular flooring tile of FIG. 1.

FIG. 3 is a bottom plan view of the modular flooring tile of FIG. 1.

FIG. 4 is a bottom isometric view of the modular flooring tile of FIG. 3; and,

FIG. 5 is a right side elevation view of the modular flooring tile of FIG. 1, where the left side elevation is the same. The broken lines in FIGS. 3 and 4 depict portions of the modular flooring tile with cable channels that form no part of the claimed design.
